IRON HOLDER

John Clark Brown, 1 Montgomery St., Belleville, N.J.

Filed Sept. 1, 1961, Ser. No. 66,586

Term of patent 14 years

(Cl. D49—6)

The side not shown has substantially the same appearance as the side shown.

The broken lines shown in FIG. 1 are for illustrative purposes only.

I claim:

The ornamental design for an iron holder as shown and described.
